CLOTHESPIN OR THE LIKE

Heinz-Hermann Weick, 94 Rue de la Serrette,
Geneva, Switzerland

Filed July 26, 1968, Ser. No. 12,923

Claims priority, application Switzerland Feb. 15, 1968

Term of patent 14 years

Int. Cl. D7—06

U.S. Cl. D49—1

FIG. 1

FIG. 2

FIG. 3

FIG. 4

FIG. 1 is a front elevation of the clothespin or the like showing my new design;

FIG. 2 is a rear elevation thereof;

FIG. 3 is a side elevation thereof;

FIG. 4 is a side elevation opposite that shown in FIG. 3.

The dominant features of my design reside in the portions shown in full lines.

I claim:

The ornamental design for a clothespin or the like, substantially as shown and described.
